(57) **CLAIM**

The ornamental design for a ventilating fan as shown and described.

DESCRIPTION

1. Ventilating fan
2. Ventilating fan
3. Ventilating fan
- 1.1 : Perspective
- 1.2 : Right
- 1.3 : Left
- 1.4 : Front
- 1.5 : Back
- 1.6 : Perspective
- 2.1 : Left
- 2.2 : Perspective
- 2.3 : Front
- 2.4 : Right
- 2.5 : Perspective
- 2.6 : Back
- 3.1 : Front
- 3.2 : Right
- 3.3 : Back
- 3.4 : Perspective
- 3.5 : Left
- 3.6 : Perspective

The broken lines and de-emphasized areas within broken lines depict portions of the ventilating fan that form no part of the claimed design.

The design is a fan that can be positioned at different heights; parts shown by means of broken lines in the reproductions are not part of the claimed designs; branding "Meaco" and associated logo is disclaimed in all reproductions.

(Continued)

tions on designs 1 to 3; the power cord is disclaimed in all reproductions of designs 1, 2 and 3; the display is disclaimed in the reproductions of designs 1, 2 and 3.
